UNITED STATES PATENT OFFICE.

PERCY H. THOMAS, OF PITTSBURG, PENNSYLVANIA, ASSIGNOR TO COOPER HEWITT ELECTRIC COMPANY, A CORPORATION OF NEW YORK.

ADJUSTABLE VAPOR-DISCHARGE DEVICE.

SPECIFICATION forming part of Letters Patent No. 783,483, dated February 28, 1905.

Application filed February 20, 1903. Serial No. 144,199.

To all whom it may concern:

Be it known that I, PERCY H. THOMAS, a citizen of the United States, and a resident of Pittsburgh, county of Allegheny, State of Pennsylvania, have invented certain new and useful Improvements in Adjustable Vapor-Discharge Devices, of which the following is a specification.

The qualities of the Cooper Hewitt gas or vapor electric apparatus which adapt it to serve the purposes of a spark-gap are already well known. It is known, for example, that apparatus of this character may be so constructed as to require a high voltage in order to break down the reluctance to starting which appears at the electrode, which for the time being is the negative electrode. The voltage required for breaking down this reluctance may be accurately predetermined by suitable modifications in the construction of the apparatus so that, for example, an apparatus can be made in which the initial reluctance will be broken down by a current of ten thousand volts or any other selected electrical pressure within limits. By a proper arrangement of the electrical connections to an apparatus of this sort it may be capable of acting as a discharge device for currents of opposite direction, as may be desired. Hitherto it has been customary to construct each apparatus for a definite breaking-down voltage and to adapt it in other respects either to permit discharges in one direction only or in both directions. The reluctance to starting which exists in these devices appears in the first instance at the negative electrode in the form of an electric strain, which is created when current is applied at the terminals. The breaking down of this reluctance supervenes when this strain is increased by the application of a critical strain tending to overcome the reluctance at the electrode. The measure of the pressure to be applied in order to start the apparatus into operation is the degree of critical strain required for this purpose. It has been found convenient to utilize as a point of application of the critical strain the starting-band, which usually forms a part of the vapor apparatus and which may be either a ring of metal foil

or other conducting material arranged near 50 one or both of the electrodes or a strip of similar material occupying the same position. It is found that the starting-band is most effective for reducing the needful amount of critical strain when it is placed in close proximity to the negative electrode, and the necessary strain is increased when the starting-band is placed farther away from the electrode.

It is the object of the present invention to 60 provide means whereby a vapor-discharge device of this general character may be constructed so as to be adjustable—that is to say, so that a given device may be adapted to discharge under different pressures. 65

The invention is illustrated in the accompanying drawings, in which—

Figure 1 is an elevation of an adjustable vapor-discharge device adapted to permit discharges in one direction only, and Fig. 2 is a 70 similar view of a device permitting discharges in opposite directions.

In the drawings, 1 is a suitable container enclosing a conducting gas or vapor and provided with suitable electrodes 2 and 3. These 75 electrodes are here represented as being of mercury, although it is not desired to limit the invention to the employment of mercury terminals only. The electrodes 2 and 3 are connected, respectively, to leading-in wires 4 80 and 5 and through these wires to the conductors 6 and 7 of an electric circuit.

On the outside of the container 1, as shown in Fig. 1, and in proximity to the negative electrode 3 I place starting-bands 8 8, the 85 lower ends of the starting-bands being variously disposed with relation to the surface of the electrode. The upper ends of said starting-bands may be connected one at a time with a switch-arm 9, which is pivoted at any 90 convenient point, and is connected by a wire 10 with the leading-in wire 4 at the opposite side of the apparatus. Owing to the characteristics set forth in the preamble of this specification, it is manifest that the apparatus will 95 start under lower pressure if the switch-arm is connected with the starting-band which extends in Fig. 1 below the surface of the nega-

tive electrode. The pressure required for starting may then be increased by moving the switch-arm into connection with one or the other of the more remote starting-bands. In 5 this way the desired feature of adjustability is obtained.

In Fig. 1 the starting-bands are applied only to the electrode at one end of the apparatus, in consequence of which the breaking down 10 will take place under ordinary conditions only at the electrode selected, and the discharge-current will pass through the apparatus from the positive electrode 2 to the negative electrode 3. In Fig. 2 the discharge may take 15 place in either direction, inasmuch as I provide starting-bands 8 8 8 in proximity to each of the electrodes. I also provide means for shifting the connections of the several starting-bands, so as to vary the pressure at 20 either electrode under which the breaking-down strain must be applied. In other respects the action of the device illustrated in Fig. 2 is identical with that of the device already described—that is to say, the main 25 essential difference is that the apparatus of Fig. 2 is adapted to permit discharges in opposite directions, while the device of Fig. 1 permits such discharge only in a single direction.

30 It is obvious that the switch-arms 9 in the apparatus illustrated in Fig. 2 might be operated independently in case it should be desired to adapt the apparatus to discharge under different pressures in opposite directions.

35 As a simple variant of the apparatus described and shown herein I may mention the employment of a vertical adjustable ring surrounding one or both of the electrodes. The action is obvious.

40 I claim as my invention—

1. An adjustable discharge device comprising a suitable container, electrodes at least one of which is of disintegrating material, and a conducting gas or vapor, in combination with 45 means for creating within limits any desired initial strain at the contact of the gas or vapor and the disintegrating electrode.

2. An adjustable vapor-discharge device comprising a hermetically-sealed container, 50 positive and negative electrodes therein, and an inclosed gas or vapor, in combination with means for creating within limits any desired initial strain at the contact of the gas or vapor and the negative electrode.

3. An adjustable discharge device comprising a suitable container, positive and negative electrodes therein and an inclosed conducting gas or vapor, in combination with means external to the container for creating within limits any desired initial strain at the contact 60 of the gas or vapor and the negative electrode.

4. A discharge device comprising a conducting gas or vapor and electrodes therefor, such device being characterized by the property of requiring the application of a critical strain in 65 order to break down its initial reluctance to starting, in combination with a plurality of starting-bands arranged at varying distances from the surface of one or both of the electrodes, and means for making appropriate 70 electrical connections with any one of the several starting-bands at will at either or both electrodes.

5. An adjustable discharge device comprising an inclosed conducting gas or vapor and 75 electrodes therefor, an electric circuit connected to the said electrodes and adapted to impress upon the said device a definite electromotive force, in combination with means for creating within limits any desired initial strain 80 at the contact of the gas or vapor and the negative electrodes.

6. A discharge device comprising an inclosed conducting gas or vapor and electrodes therefor, an electric circuit connected to the said 85 electrodes and adapted to impress upon the said device a definite electromotive force, in combination with one or more starting-bands, and means for varying the effective relations of the starting band or bands and the negative 90 electrode.

7. A discharge device comprising an inclosed conducting gas or vapor and electrodes therefor, an electric circuit connected to the said 95 electrodes and adapted to impress upon the said device a definite electromotive force, in combination with one or more starting devices, and means for varying the effective relations of the starting device or devices and the negative electrode. 100

Signed at New York, in the county of New York and State of New York, this 14th day of February, A. D. 1903.

PERCY H. THOMAS.
